UNITED STATES PATENT OFFICE.

ALEXANDER M. HAMILTON, OF AVALON, PENNSYLVANIA.

DESIGN FOR A BOTTLE.

SPECIFICATION forming part of Design No. 32,103, dated January 16, 1900.

Application filed December 14, 1899. Serial No. 740,370. Term of patent 3½ years.

To all whom it may concern:

Be it known that I, ALEXANDER M. HAMILTON, a resident of Avalon, in the county of Allegheny and State of Pennsylvania, have 5 invented a new and useful Design for Bottles; and I do hereby declare the following to be a full, clear, and exact description thereof.

My design consists in a flat bottle having on one face thereof a horseshoe-shaped border extending from the base of the bottle upwardly and inclosing the figure of a baby.

The accompanying drawing illustrates the design in a perspective view.

In said drawing, 1 is the bottle, having sub-

stantially flat side faces 2. On one side face is the border 3, which is of horseshoe shape, the base 4 of the same being close to the bottom 5 of the bottle and said border inclosing a figure of a baby, as at 6.

What I claim is—

The design for a bottle herein shown and described.

In testimony whereof I, the said ALEXANDER M. HAMILTON, have hereunto set my hand.

ALEXANDER M. HAMILTON.
